VARIABLE MULTIPLE HEAD

Filed June 5, 1948

UNITED STATES PATENT OFFICE

2,589,485

VARIABLE MULTIPLE HEAD

Melvin H. Emrick, Jamaica, N. Y.

Application June 5, 1948, Serial No. 31,252

4 Claims. (Cl. 74—665)

1

This invention relates to a variable multiple head, otherwise known as a multiple tapping device wherein a plurality of tools are simultaneously operated at one time in drilling, tapping or performing other operations on a workpiece. More particularly, the invention deals with an adjustable device of this kind wherein each tool operating member constitutes part of a unit wherein the member of said unit is rotatably adjustable about a fixed driving shaft, and wherein a series of the units are arranged in closely nested relationship to each other, whereby the tool operating members can be positioned over substantially the entire area governed by the boundaries of rotation of each member of the unit with respect to its drive axis.

The novel features of the invention will be best understood from the following descriptions when taken together with the accompanying drawing, in which certain embodiments of the invention are disclosed, and in which the separate parts are designated by suitable reference characters in each of the views; and in which:

Fig. 1 is a sectional plan view of a device made according to my invention, the section being substantially on the line 1—1 of Fig. 2; and

Fig. 2 is a broken section, roughly on the line 2—2 of Fig. 1, showing only one unit of the device and omitting illustration of the other units for purpose of simplification in the showing.

In devices of the type and kind under consideration, which are generally classified as "multiple tapping attachments," it has been customary to provide attachments wherein the tool operating member of each unit of the attachment had a limited range of positioning so that the positioning of the tool operating member with respect to a workpiece was limited, thus making it necessary to employ, in a shop, a number of devices of this kind in order to be able to meet varying conditions that would prevail from time to time in drilling and tapping, or in performing other operations in a workpiece.

The purpose of my invention is to provide a device of the kind under consideration which may be said to provide a substantially universal adjustment of tools or tool operating members, so as to position the same at any desired location on a workpiece within the area of adjustment provided by the size of the device employed.

In accomplishing this result, the device is made up of a multiplicity of adjustable units, each unit having two distinct phases of adjustment. That is to say, the adjustment of an idler shaft around a drive shaft fixed in the casing of the

device, and the adjustment of a tool operating member around said idler shaft, thereby enabling the members of each unit to be positioned in any given alignment, or in any other staggered relationship with respect to each other within a range governed only by the radius defined between the axes of the drive shaft and idler shaft and that of the tool operating member, the latter being further controlled by positioning of the drive axes of each unit in the casing of the device.

In Fig. 2 of the drawing, I have indicated at 10, part of an adaptor head employed for mounting and actuating devices 11 of the general type and kind under consideration. The device 11 comprises a casing having upper and lower case parts 12 and 13. Suitably supported in these case parts in bearings 14 and 15, is a main drive shaft 16 of the device, which has an upwardly extending hexagon or other end 17 for coupling with the drive of the adaptor 10, as is known in devices of this type and kind.

On the shaft 16, within the casing 11, is a drive pinion 18, adapted to drive a series of idler gears 19, 20 and 21, mounted on shafts 22, 23 and 24 fixed in the casing 11. This gearing is adapted to drive three independent adjustable units, generally identified by the reference characters 25, 26 and 27. In that each unit is identical in construction, the same references will be applied to the respective units, and primed, as seen in Fig. 1. In order to simplify the illustration, only one of the units is shown in Fig. 2.

Each unit comprises a shaft 28, 28' and 28'', which will define the drive shaft of the unit, and is mounted or fixed in the casing 11 and fixed to the shaft is a double faced pinion 29, 29' and 29'', the upper face of the pinion meshing with the gears 19, 20 and 21 respectively, as clearly seen in Fig. 1. The lower face of the pinion 19, 19' and 19'' mesh with another double faced gear 30, 30' and 30'' mounted on an idler bolt shaft 31, 31' and 31''.

As clearly seen in Fig. 2 of the drawing, the upper gear face of the gears 30, 30' and 30'' mesh with the lower gear face of said first named double faced gears. Whereas, the lower gear face of the gears 30, 30' and 30'' mesh with pinions 32, 32' and 32'' on tool supporting members 33, 33' and 33''. In that the remainder of the units 25, 26 and 27 is shown only of the unit 25, in Fig. 2, this mechanism will be limited to the unit 25, but it will be understood that similar mechanism is employed in conjunction with each of the respective units.

55 Rotatably mounted in the lower part 13 of the

casing 12, is a flanged disc 34 having a large central aperture 35 through which the shaft 28 and the double faced gear 29 is free to pass. The disc 34 has the shaft bolt 31 coupled therewith, at a predetermined distance with respect to the axis 28. The disc 34 protrudes through the lower face of the bottom part 13 of the casing, and mounted on the disc and seating on the casing is a gear housing 36 in which the shaft 28 has a bearing.

At one side of the housing is a large aperture 37 in which is fitted another gear housing 38, in which the tool operating member 33 is supported. The housing 38 has at its inner end, a thrust bearing 39 for support of the inner end of the member, and also includes a roller bearing 40 for free rotation of the member 33 therein. Below the housing 38 is another housing 41 having a bearing 42 for the member 33 and also apertured, as seen at 43, to receive the lower threaded end of the bolt shaft 31.

From the foregoing, it will appear that the upper head end 44 of the bolt shaft 31 seats upon the flanged disc 34. A split nut 45 is mounted on the lower end of the bolt shaft 31 to retain the housings 36, 38 and 41 in coupled relationship with each other and with the disc 34 and the casing 11 or the lower part 13 thereof.

This securing of the parts together is sufficient to hold said parts in assembled relationship while permitting rotary adjustment of the parts one with respect to the other in the manner later described. When the member 33 has been brought into the desired position, the parts are secured together by a clamp nut 46, preferably of the type having a socket 47 for the reception of the tightening screw.

In adjusting each of the units, the nut 46 is loosened and the bolt shaft 31 can then be freely rotated around the axis of the drive shaft 28 of the unit and the tool supporting member 33 can also be rotatably adjusted around the bolt shaft 31, thereby the member 32 can be positioned in any desired position with respect to the greatest radial distance between the combined axes 28, 31 and 33, and within the field covered by this greatest distance. It will thus be understood that by positioning the shafts 28 in the casing 11, in the closely nested relationship shown, the tools of the three units can operate within what may be termed a "three clover-leaf field" defined by the mechanism adjustment of the members 33, 33' and 33''.

In the accompanying drawing, as seen in Fig. 1, the various units have been adjusted so as to bring the members 33, 33' and 33'' in the straight alignment shown. That is, perpendicularly straight, as appearing in the drawing, with all of the members disposed at one side of, and to the right of the primary drive shaft 16. This particular illustration has been shown, as it is one of the difficult adjustments to be provided. It will be understood, however, that the members 33 can be brought into as close a relationship to each other as will be possible by the structure of the supporting parts or housings of the respective units.

From a standpoint of description, the bolt shafts of each unit may be characterized as idlers of the gear shown in each unit, and thus considered, the idlers are rotated about the drive axis of the unit while the tool members rotate about the axis of the idlers.

In devices or apparatus of the kind under consideration, the adaptors 10 are usually mounted for sliding movement on guide rods or tubes 48

passing through bearing portions 49 on the adaptor and as seen in Fig. 2 of the drawing, the bearing portions 49 may include parts 49' engaging the peripheral recess 50 of the casing 11. Also secured in the recess 50 of the casing 11, are other bearings, one of which is shown at 51, in Fig. 2 of the drawing, and two of which are indicated in Fig. 1. These latter bearings 51 support rods 52 which in turn support templets 53 which guide the setting of the tool supporting members 33 or the housings 41 thereof with respect to the resulting workpiece. In other words, a templet plate 53 will be accurately formed to position the various members 33, 33' and 33'', one with respect to the other. The setting of said tool supporting members is thus materially simplified. The plate 53 has other apertures 54 provided therein in registering alignment with the sockets 47 of the nuts 46 to facilitate clamping the various units in adjusted position.

In other words, a shop having one of the "multiple adjustable devices" can adapt this device to perform many drilling, tapping or other operations on a workpiece within the range of adjustment as aforesaid, by simply constructing templet plates 53 to suit the different jobs or operations to be performed. Thus, a single device may be utilized to perform many operations in multiple drilling, tapping or the like.

It will, of course, be understood that device of this type and kind can be made in different sizes and also with a different arrangement of fixed axes of drive, that is, the axes 28, 28' and 28''. Certain shops having work of a particular type and character may require settings of these axis centers on different positions on the device to be more suitable for the particular type and kind of work in connection with which the device is employed. The accompanying illustration is shown to illustrate the closely, and what may be termed, the "closely huddled arrangement" of the units. From this can be produced a greater wide spread of units and a greater number of units can be employed.

Having fully described my invention, what I claim as new and desire to secure by Letters Patent is:

1. In variable multiple heads of the character described, a casing including an integral bottom wall, a main drive shaft having a fixed position in the casing, a plurality of tool operating units, means for simultaneously driving all of the units from said main drive shaft, each unit comprising a supplemental drive shaft having a fixed position in the casing, a flanged disc rotatably adjustable in and supported by said bottom wall of the casing, the flange of said disc seating on said bottom wall, an idler shaft mounted in said disc and adjusted around the axis of the supplemental drive shaft by said disc, a tool supporting member rotatably adjustable around the idler shaft, a gear train on said shafts and member for operating said member, each unit comprising a housing rotatable about the supplemental drive shaft of the unit and another two-part housing rotatable about said idler shaft, means on said idler shaft engaging said last named housing for retaining the housings and disc in assembled relationship with each other and with the casing, and other means on said idler shaft engaging said last named housing independently of the last named means for fixing said housings and disc in firm engagement with the casing in retaining the tool

supporting member in a fixed position of adjustment.

2. In variable multiple heads of the character described, a casing including an integral bottom wall, a main drive shaft having a fixed position in the casing, a plurality of tool operating units, means for simultaneously driving all of the units from said main drive shaft, each unit comprising a supplemental drive shaft having a fixed position in the casing, a flanged disc rotatably adjustable in and supported by said bottom wall of the casing, an idler shaft mounted in said disc and adjusted around the axis of the supplemental drive shaft by said disc, a tool supporting member rotatably adjustable around the idler shaft, a gear train on said shafts and member for operating said member, each unit comprising a housing rotatable about the supplemental drive shaft of the unit and another two-part housing rotatable about said idler shaft, means on said idler shaft retaining the housings and disc in assembled relationship with each other and with the casing, other means on said idler shaft for fixing said housings and disc in firm engagement with the casing in retaining the tool supporting member in a fixed position of adjustment, said disc protruding through the bottom of said casing, and said first named housing being rotatably adjustable on the protruding portion of said disc.

3. In variable multiple heads of the character described, a casing including an integral bottom wall, a main drive shaft having a fixed position in the casing, a plurality of tool operating units, means for simultaneously driving all of the units from said main drive shaft, each unit comprising a supplemental drive shaft having a fixed position in the casing, a flanged disc rotatably adjustable in and supported by said bottom wall of the casing, an idler shaft mounted in said disc and adjusted around the axis of the supplemental drive shaft by said disc, a tool supporting member rotatably adjustable around the idler shaft, a gear train on said shafts and member for operating said member, each unit comprising a housing rotatable about the supplemental drive shaft of the unit and another two-part housing rotatable about said idler shaft, means on said idler shaft retaining the housings and disc in assembled relationship with each other and with the casing, other means on said idler shaft for fixing said housings and disc in firm engagement with the casing in retaining the tool supporting member in a fixed position of adjustment, said disc protruding through the bottom of said casing, said

first named housing being rotatably adjustable on the protruding portion of said disc, and one part of the second named housing extending into and having a bearing in said first named housing.

4. In variable multiple heads of the character described, a casing including an integral bottom wall, a main drive shaft having a fixed position in the casing, a plurality of tool operating units, means for simultaneously driving all of the units from said main drive shaft, each unit comprising a supplemental drive shaft having a fixed position in the casing, a flanged disc rotatably adjustable in and supported by said bottom wall of the casing, an idler shaft mounted in said disc and adjusted around the axis of the supplemental drive shaft by said disc, a tool supporting member rotatably adjustable around the idler shaft, a gear train on said shafts and member for operating said member, each unit comprising a housing rotatable about the supplemental drive shaft of the unit and another two-part housing rotatable about said idler shaft, means on said idler shaft retaining the housings and disc in assembled relationship with each other and with the casing, other means on said idler shaft for fixing said housings and disc in firm engagement with the casing in retaining the tool supporting member in a fixed position of adjustment, said disc protruding through the bottom of said casing, said first named housing being rotatably adjustable on the protruding portion of said disc, one part of the second named housing extending into and having a bearing in said first named housing, a roller bearing for the tool supporting member in each part of the second housing, and a thrust-bearing for said member in one of the housing parts.
